DESIGN FOR A CAB BODY OR THE LIKE

Robert L. Allen, Battle Creek, Mich.

Application February 1, 1945, Serial No. 117,713

Term of patent 14 years

(Cl. D14—3)

To all whom it may concern:

Be it known that I, Robert L. Allen, a citizen of the United States, residing at Battle Creek, in the county of Calhoun and State of Michigan, have invented a new, original, and ornamental Design for a Cab Body or the like, of which the following is a specification, reference being had to the accompanying drawing, forming part thereof.

I claim:

The ornamental design for a cab body or the like, substantially as shown.

ROBERT L. ALLEN.
